UNITED STATES PATENT OFFICE.

JOHN CALDWELL, OF PHILADELPHIA, PENNSYLVANIA.

INSULATOR FOR ELECTRIC WIRES.

No. 879,033.

Specification of Letters Patent.

Patented Feb. 11, 1908.

Application filed August 7, 1907. Serial No. 387,516.

To all whom it may concern:

Be it known that I, JOHN CALDWELL, a citizen of the United States, residing at Philadelphia, in the county of Philadelphia and 5 State of Pennsylvania, have invented certain new and useful Improvements in Insulators for Electric Wires; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this specification. 15

This invention relates to new and useful improvements in insulators for electric wires and the object in view is to produce a means whereby the line wire may be prevented from 20 twisting or slipping, and consists essentially in the provision of an insulator having a triangular outlined groove formed preferably above the core of the insulator.

My invention comprises various details of 25 construction and combinations and arrangements of parts which will be hereinafter fully described and then specifically defined in the appended claims.

I illustrate my invention in the accompanying drawings, in which:—

Figure 1 is a perspective view of my insulator. Fig. 2 is a sectional view through the insulator, and Fig. 3 is a side elevation.

Reference now being had to the details of 35 the drawings by letter, A designates an insulator, preferably of the usual shape, provided with a hollow center for the reception of a supporter.

B designates a groove, the bottom of which 40 is of triangular shape, having preferably three angles, and said groove adjacent to the ends of the angles is widened as at D, as shown, for the purpose of facilitating the tying of the wire and of relieving parts of the 45 insulator from the strain in tying.

E designates a tie wire, which is passed about one of the angles in the groove or recess and its ends are twisted about the line wire, which latter is held in the recess and against one of the straight portions of the 50 bottom of the recess.

By the provision of the peculiarly formed insulator embodying my invention, hard drawn copper wire may be fastened securely without twisting or kinking the line wire and 55 which it is found possible to do when the wire is fastened to a circular groove of an insulator. As hard drawn copper wire is exceedingly brittle, it will not stand the bending and twisting that iron wire will and the fact of the 60 wires used upon the circular outlined recesses of insulators not standing the bending and twisting which comes upon them has been the means of a great deal of trouble that electrical companies have had to contend 65 with.

What I claim to be new is:—

1. An insulator having a groove at right angles to its length, the bottom of said groove forming the three faces of the triangle, a line 70 wire held against one of the straight faces of the bottom of the groove, and a tie wire engaging the other two faces and fastened about the line wire, as set forth.

2. An insulator having a groove at right 75 angles to its length, the bottom of said groove forming the three faces of the triangle, a line wire held against one of the straight faces of the bottom of the groove, a tie wire engaging the other two faces and fastened about the 80 line wire, said groove having widened portions at the angles formed by the straight faces forming the bottom of the groove, as set forth.

In testimony whereof I hereunto affix my 85 signature in the presence of two witnesses.

JOHN CALDWELL.
